DESIGN FOR A TEXTILE FABRIC

Abraham Nelson Harrison, New York, N. Y.

Application June 29, 1933. Serial No. 48,586

Term of patent 3½ years

To all whom it may concern:

Be it known that I, ABRAHAM NELSON HARRISON, a citizen of United States, residing at the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design. A single unit of my design is substantially shown on the drawing.

I claim:

The ornamental design for a textile fabric, substantially as shown and described.

ABRAHAM NELSON HARRISON.
